UNITED STATES PATENT OFFICE.

ELDER E. ANDERSON, OF MINNEAPOLIS, MINNESOTA.

SPRING WHEEL.

Application filed June 3, 1922. Serial No. 565,561.

To all whom it may concern:

Be it known that I, ELDER E. ANDERSON, a citizen of the United States, residing at Minneapolis, in the county of Hennepin and 5 State of Minnesota, have invented certain new and useful Improvements in Spring Wheels, of which the following is a specification.

The present invention relates to spring 10 wheels and has for its principal object to provide spring means between the tire or rim and the felly of the wheel.

Another important object of the invention is to provide means between the felly and 15 the rim for imparting the rotary motion of the former to the latter, said means being of a resilient nature.

A still further object of the invention is to generally improve upon spring wheels 20 of this character by providing a device which will be extremely simple in construction, reliable in operation, capable of being manufactured at a comparatively low cost, and well adapted to the purpose for which 25 it is designed.

In the drawing:—

Figure 1 is a fragmentary elevation of a 30 wheel embodying my invention, portions thereof being shown in section,

Figure 2 is a transverse section taken therethrough,

Figure 3 is a fragmentary longitudinal section through a portion of the wheel,

Figure 4 is a transverse section there- 35 through taken substantially on the line 4—4 of Figure 1 looking in the direction of the arrow,

Figure 5 is a detailed longitudinal section 40 showing interior portions of the wheel in elevation, and

Figure 6 is a transverse section through the wheel taken substantially on the line 6—6 of Figure 1 looking in the direction of the arrow.

Referring to the drawing in detail it will 45 be seen that a hub of any preferred construction 1 is provided with the conventional spokes 2 extending therefrom and upon these spokes there is mounted a felly 3. A U-shaped annular plate 4 is mounted on the outer periphery of the felly 3 and has circular plates 5 attached thereto and spaced therefrom by the rings 6. These circular plates 5 are provided with recesses 7 for 50 receiving suitable packing 8. A pair of circular plates 9 are associated with the plates

5 so as to engage their inner faces as is shown to advantage in Figure 4. These inner plates 9 are attached to the flanges of the rim 10 which has mounted thereon a 60 demountable rim 11 of any preferred construction on which is carried a tire 12 either solid as shown or pneumatic or of any other preferred construction.

A plurality of curved substantially U-shaped springs 13 are disposed between the rim 10 and the plate 4 attached to the felly 3. These springs have their ends terminating in eye members for receiving the bolts 15 which pass through the flanges of the rim 70 10 and through the flanges of the plate 4 thus resiliently mounting the rim 10 in respect to the felly 3. It will be seen that the plates 9 and 5 form a housing for these springs and for other parts to be described 75 hereinafter.

A plurality of boxes 16 are disposed between the springs 13 and are constructed with open inner ends. A bolt 17 extends longitudinally of each box 16 adjacent its 80 inner end and is fixed in place by nuts 18 or some such other suitable means. Suitable flanges 19 are provided at the outer end of each box 16 and these flanges are riveted to the rim 10 in any suitable manner such 85 as is shown at 20. Inside of each box adjacent the other end there is mounted a suitable resilient lining or member 21 for a purpose which will be evident hereafter.

A plurality of plungers 22 radiate from 90 the base of the U-shaped plate 4 being held in place by having their flanges 23 riveted thereto as at 24 or in any other suitable manner. The outer ends of these plungers are slotted as at 25 for receiving the bolts 95 17 in the boxes 16. A pair of springs 27 is mounted on each of the bolts 17 one on each side of the plunger 22 situated adjacent thereto. The springs 13 normally hold the rim separated from the felly and thus 100 the parts will be positioned substantially as is disclosed in Figure 1. When the springs 13 are compressed the outer end of each plunger will move toward the outer end of its corresponding box and may even abut 105 the resilient lining 21. The springs 27 take up any shock which will be caused by the movement of the felly such as when the clutch is first let in upon an automobile and thus there would not be such a jar as the 110 machine was first propelled forwardly or rearwardly. This structure, of course, is

adapted to other vehicles and uses this particular one merely being given by way of example.

It is to be understood that the present embodiment of the invention has merely been disclosed by way of example and that numerous changes in form, material, and in the combination and arrangement of parts as may be resorted to without departing from the spirit of the invention as hereinafter claimed.

Having thus described my invention what I claim as new is:—

In combination, a felly, a rim spaced from the felly, a resilient member disposed be-

tween the felly and the rim, a plurality of boxes attached to the rim, plungers extending from the felly into the boxes, a bolt extending longitudinally of each of the boxes, said plungers being provided with elongated slots for receiving said bolts, and spring elements disposed on each bolt one on each side of each plunger. 20

In testimony whereof I affix my signature in presence of two witnesses.

ELDER E. ANDERSON.
